UNITED STATES PATENT OFFICE.

EMIL GATHMANN, OF NEW YORK, N. Y.

INGOT-MOLD.

1,019,244.

Specification of Letters Patent.

Patented Mar. 5, 1912.

Application filed August 15, 1911. Serial No. 644,103.

To all whom it may concern:

Be it known that I, EMIL GATHMANN, a citizen of the United States, residing in the city, county, and State of New York, have 5 invented certain new and useful Improvements in Ingot-Molds, of which the following is a specification.

My invention relates to certain improvements in the construction of ingot molds and 10 in the stools for sealing the lower portion or bottom of the mold chambers.

The invention particularly relates to molds of this class in which the larger part of the mold is uppermost. Molds of this 15 kind are open at top and bottom, the bottom being closed when casting by means of a "stool" on which the mold rests. Inasmuch as the mold is separable from the stool, the molten metal will leak from the mold chamber 20 unless some means be provided for sealing the joint between the mold and the stool. Heretofore this has been accomplished by a fire-brick or clay construction which is not only expensive but it is insufficient, because 25 often some dampness or moisture remains in the fire clay which, when the metal is teemed produces steam that enters the molten metal, becomes dissociated and forms gases which produce blow holes that will 30 greatly impair the ingot. Furthermore when the bottom of the mold rests on a metallic stool it is practically impossible in this way to provide an absolute seal and some of the molten metal leaks out laterally 35 from the mold chamber and forms a fin at the lower part of the ingot producing a construction which makes it difficult to strip the ingot from the mold.

According to my invention I form a seal 40 within the mold chamber which effectively prevents the egress of the molten metal therefrom. Preferably the stool is formed with a part which projects into the lower portion of the mold chamber and the seal 45 is formed by refractory material which surrounds the projection. Preferably also the seal extends beneath the lower or base walls of the mold and underneath the lower outer portion of the mold chamber and in one 50 form of the invention the stool is formed with a flange which surrounds the projection and which enters a recess or groove in the bottom of the mold walls.

In the accompanying drawings, Figure 1 55 is a vertical central section through an ingot mold embodying my improvements.

Fig. 2 is a similar view of another form of mold with my improvements applied showing the stool resting on a transfer car.

The mold shown in Fig. 1 is preferably so 60 constructed as to prevent the formation of pipes or blow-holes in the ingot. This feature of my invention is however described and claimed in other patents granted to me.

Referring to Fig. 1, the mold body A 65 rests on a stool B of novel construction. *a* indicates lifting lugs and *a'* trunnions. The stool is provided with an upwardly projecting centrally arranged part *b* which enters the lower portion of the mold chamber. The 70 diameter of the projection is less than that of the mold chamber leaving a surrounding space *x* which is filled with fire-clay, molders' earth or the like, *y*. Preferably a groove *b'* is made to surround the lower part of the 75 projection *b* and a flange or rib *c* surrounds the groove and a refractory material fills this groove as well as the space surrounding the projection within the mold chamber. The mold rests on the rib *c* and preferably 80 the bottom wall of the mold is formed with a recess *d* into which the rib *c* enters so that a rib *e* on the inside of the groove enters the recess *b'*, while a rib *f* outside the groove projects below the plane of the bottom of 85 the rib *e* and serves to protect it when the mold is removed from the stool and is supported on something else.

In assembling the parts, refractory material is placed in the groove *b'* and in the 90 space *x* around the projection *b*, then the mold is lowered onto the stool and the sealing medium will assume the condition indicated. When the mold is teemed the molten metal will bear heavily upon the 95 seal, but no metal can pass laterally out of the mold chamber or beneath the mold walls and thus the production of lateral fins which would interfere with the stripping of the mold is prevented.

In Fig. 2 the stool B' is shown mounted 100 on a car C resting on rails D. In this case the stool is formed with a part *b* which enters the mold chamber and a recess *h* formed around the projection which extends below the plane of the bottom of the mold walls. The bottom of the recess is inclined upward and outward and the bottom of the mold walls is similarly inclined but more gradually. The space *x* surrounding the projection *b* within the mold chamber is filled with refractory material 105

y' and the space below the mold and above the bottom of the groove or recess *h* is similarly filled. The mold rests on the stool at the outer edge thereof surrounding the 5 groove *h*. In this case also the leaking of metal laterally below the mold is prevented as the sealing medium can never sink sufficiently to allow any metal to pass out laterally from the mold. In Fig. 2 the mold 10 *A'* is shown as being provided with lifting lugs *a'*.

In operating with either of the molds shown in Figs. 1 or 2, after the teeming of the ingot the car *C* is taken to the stripping 15 department and the mold with the contained ingot is lifted from the stool *B* by crane mechanism of well known kinds.

I claim as my invention:—

1. A metallic ingot mold separably connected with a metallic stool having a part projecting into the lower portion of the mold chamber which is out of contact with the vertical walls of said chamber and is provided with means for preventing the 25 molten metal of the ingot from passing laterally outward from said chamber.

2. A metallic ingot mold separably connected with a metallic stool having a part projecting into the lower portion of the 30 mold chamber which is out of contact with the vertical walls of said chamber and which has sealing means surrounding its vertical walls.

3. A metallic ingot mold separably connected with a metallic stool having a part projecting into the lower portion of the mold chamber and having sealing means 35 located between the lower vertical chamber walls of the mold and the inwardly projecting portion of the stool.

4. An ingot mold separably connected with a stool having a part projecting into the mold chamber and having sealing means of refractory material interposed between

the vertical walls of the mold and said projecting part. 45

5. A chambered mold resting on and separably connected with a stool having a part projecting into the mold chamber surrounded by a groove which extends below 50 the mold base and underneath the lower outer portion of the mold chamber and which groove is filled with sealing material.

6. A metallic stool for ingot molds having a part adapted to project into the lower 55 portion of the mold chamber, said projecting part being surrounded by a groove or gutter adapted to extend below the mold base and underneath the lower portion of the mold chamber. 60

7. A metallic stool for ingot molds having a part adapted to project into the lower portion of the mold chamber, said projecting part being surrounded by a groove or gutter adapted to extend below the mold 65 base and underneath the lower outer portion of the mold chamber, in combination with sealing material placed in said groove or gutter.

8. A metal stool for chambered ingot 70 molds provided with an annular groove or gutter adapted to extend below the mold base and underneath the lower outer portion of the mold chamber.

9. A metallic stool for chambered ingot 75 molds provided with an annular groove or gutter adapted to extend below the mold base and underneath the lower portion of the mold chamber, in combination with a sealing material placed in said groove or 80 gutter.

In testimony whereof, I have hereunto subscribed my name.

EMIL GATHMANN.
